UNITED STATES PATENT OFFICE.

JOHN P. REINIG, OF BUFFALO, NEW YORK.

HOOK.

1,260,710.

Specification of Letters Patent. Patented Mar. 26, 1918.

Application filed October 25, 1917. Serial No. 198,367.

To all whom it may concern:

Be it known that I, JOHN P. REINIG, a citizen of the United States, residing at Buffalo, in the county of Erie and State 5 of New York, have invented new and useful Improvements in Hooks, of which the following is a specification.

This invention relates to a hook designed more particularly for connecting suspenders 10 to trousers, but the same is also useful for other purposes.

One of the objects of my invention is the provision of an inexpensive fastening of this kind which permits a ready engagement with 15 and disengagement from a suitable eye-member.

A further object is to so construct the hook that it is firmly and reliably anchored in the goods to which it is attached.

20 In the accompanying drawings:

Figure 1 is a fragmentary view of a waistband and a suspender-end provided with the hook. Fig. 2 is a vertical section on line 2—2, Fig. 1. Fig. 3 is a perspective 25 view of the hook-member.

Similar characters of reference indicate corresponding parts throughout the several views.

1 indicates the cloth facing, 2 the canvas 30 reinforcement and 3 the lining of a pair of trousers at the waistband. 4 indicates a suspender-end.

Attached to the waistband is an eye-member 6 of any suitable construction.

35 The hook is preferably bent from a single length of spring wire and comprises the shank 10, the bill or hook proper 11, a keeper 12 and transverse stops or anchoring bars 13. The bill is comparatively short, as 40 shown, and the keeper extends to, or nearly to, the free end of the bill but is not interlocked with it. While preventing accidental disengagement of the bill from the eye-member, the keeper can by this construction 45 be sprung laterally as well as toward the shank 10. This enables the hook and eye

members to be easily and quickly separated, and by making the bill rather short, as shown, it can be conveniently disengaged by a relatively slight movement. 50

The bend which connects the shank of the hook with the keeper passes through the material of the suspender end, and the portion of the shank adjacent to the lower side of the cross bars 13 also penetrates the material. Both the bend and the cross bars thus receive the strain on the hook member and firmly anchor it to the suspender-end or equivalent part. 55

As shown, the keeper consists of a straight 60 bar formed of a single thickness of wire, while the bill, the shank and the cross bars contain two thicknesses which are formed by doubling the wire on itself, giving the keeper the requisite resilience and the other 65 parts the necessary strength and stiffness.

I claim as my invention:

1. A hook provided with a comparatively 70 short bill and a keeper extending to the free end of the bill without interlocking therewith, whereby the keeper is free to be deflected laterally as well as toward the shank of the hook-member.

2. A hook provided with a comparatively 75 short bill, and a keeper, consisting of a straight resilient bar arranged substantially parallel with the shank of the bill and extending from the farther end of the shank to the free end of the bill without interlocking therewith. 80

3. A hook comprising a shank provided between its ends with cross-bars, a bill at one end of the shank and a keeper-bar extending from the opposite end of the shank and terminating at the free end of the bill 85 without interlocking therewith, said hook being bent from a single length of wire and said keeper containing a single thickness and the remaining parts of the hook a double thickness of wire. 85

JOHN P. REINIG.
